UNITED STATES PATENT OFFICE.

CLARK F. RIGBY, OF MANNINGTON, WEST VIRGINIA.

ROD-PACKING.

SPECIFICATION forming part of Letters Patent No. 572,910, dated December 8, 1896.

Application filed November 19, 1895. Serial No. 569,438. (No model.)

To all whom it may concern:

Be it known that I, CLARK F. RIGBY, of 5
Mannington, in the county of Marion and State
of West Virginia, have invented certain new
and useful Improvements in Rod-Packings;
and I do hereby declare the following to be a
full, clear, and exact description of the in-
vention, such as will enable others skilled in
the art to which it pertains to make and use
10 it, reference being had to the accompanying
drawings, which form part of this specifica-
tion.

This invention pertains to rod-packing;
and the object of the invention is to provide
15 an improved combined metallic and soft pack-
ing for forming a fluid-tight joint.

The invention consists in the novel features
of construction hereinafter fully described
20 and claimed, and illustrated by the accom-
panying drawings, in which—

Figure 1 is a longitudinal sectional view of
the stuffing-box and gland, the major portion
25 of the metallic packing-rings, as well as the
piston and gland-secur ing bolt, being shown
in elevation. Fig. 2 is a detail perspective
view of one of the packing-rings.

A is the stuffing-box, and B the piston. The
interior of the stuffing-box is of greater di-
ameter than the piston, and arranged at the
30 inner end or base of the stuffing-box is the
inwardly-flared ring C. Resting upon this
base-ring and arranged in succession around
the piston are packing-rings D, each ring being
25 split at E and sprung or expanded slightly, so
as to permit of contraction when subjected
to circumferential pressure, the packing-ring
in its normal state being illustrated in Fig. 2.
The rings are here shown as arranged about
35 the piston nearly to the outer end of the stuff-
ing-box, but the rings are of less diameter
than the interior of said box, and this remain-
ing space is occupied by the longitudinally-
adjustable gland, which fits closely the same
40 and which is held and adjusted by bolts F in
the usual manner. The gland being recessed
sufficiently to inclose packing-rings D a space
G occurs between the upper end of the inter-
ior of the gland and the packing-rings D, and
45 confined in this space is the heavy coiled
spring H. Arranged beneath the gland and
between the packing-rings D and the wall of
the stuffing-box A is the asbestos or other soft

rod-packing I, which is compressed by the in-
ward longitudinal movement of the gland, the
lower end of the latter being beveled inward
55 and upward, as indicated at J, which, in
conjunction with the beveled ring C, tends to
create an inward pressure of the soft pack-
ing against the packing-rings D, as will be
understood. The pressure is so gaged as to
60 create only a slight contraction of the packing-
rings, so as to close snugly around the piston,
but not sufficiently tight to bind the same.
The coiled spring holds the packing-rings in
place and at the same time permits slight
65 longitudinal compensation of the rings, if
necessary.

Heretofore it has been proposed to provide
packing-rings adapted to fit within the gland,
the latter pressing soft packing between the
70 rings and box, and to this no broad claim is
laid. It has also been proposed heretofore to
arrange packing-boxes of the above descrip-
tion with soft packing within the gland above
the metallic rings and surrounding rod.
75 These arrangements are deficient for the rea-
sons that lint from the packing works into
the piston-chamber, thus necessitating fre-
quent cleaning of the latter, and, further, the
soft packing when placed under great pres-
80 sure by the gland becomes greatly worn and
loses its elasticity, so that in order to keep
tight the metallic rings the gland must be
frequently adjusted, and repeated renewals
85 of the soft packing is necessary.

My present invention is designed to obviate
the difficulties noted by dispensing altogether
with soft packing in contact with the rod and
substitute therefor a spring, which is arranged
between the gland and rings and the ten-
90 sion of which, as created by the gland press-
ing thereon, holds the rings in proper place
at all times. Very little adjustment of the
glands is necessary, and the use of soft pack-
ing in contact with the rod, which is objec-
95 tionable, is avoided. At no point is the rod
exposed to soft packing, and thus no lint or
particles can work into the chamber.

With my improvement greater economy
may be practiced, as there is not the contin-
ual waste of packing, and the box will be
100 found more effectual than those heretofore
employed.

Having thus fully described my invention,

what I claim, and desire to secure by Letters Patent, is—

The rod-packing shown and described comprising the rod, the stuffing-box, the bottom ring C therein, the split packing-rings on ring C, and surrounding the rod, the body of soft packing surrounding the packing-rings and resting on ring C, the portion of ring C on which the body of soft packing rests flared inwardly, the expansive coiled spring H surrounding the rod and bearing on the top packing-ring and yieldingly holding said rings to their work without excessive pressure or

twisting or jamming, and the adjustable gland inclosing the spring and holding it to its work ¹⁵ and provided with the extension inclosing the upper rings and having the beveled end pressing the soft packing against the rings, substantially as described.

In testimony whereof I affix my signature ²⁰ in presence of two witnesses.

CLARK F. RIGBY.
